HYDRAULIC APPARATUS EMBODYING A PLURALITY OF SELECTIVELY CONTROLLED CYLINDERS

Maximiliaan Frederik Gunning, Petersfield, England, and Robert C. Russell, Roslin, Scotland; said Russell assignor to said Gunning

Application July 11, 1947, Serial No. 760,434
In Great Britain July 29, 1946

6 Claims. (Cl. 60—97)

1
This invention has reference to hydraulic apparatus embodying a plurality of selectively controlled cylinders or motors.

Hydraulic apparatus embodying a plurality of cylinders which can be selectively controlled have been designed for use on constant pressure systems, a manually operated selector valve, or valves, being provided by which, depending on the work to be done or the torque to be developed, the desired cylinder or combination of cylinders can be supplied with pressure liquid.

In our British Patent No. 576,074, corresponding to U.S. Patent No. 2,442,125, we have set forth a motor of this description but the present invention is also applicable to other hydraulic apparatus embodying a plurality of cylinders of the same or different diameters, and which is provided with a selector valve or valves by which the desired cylinder or combination of cylinders can be brought into operation to meet prevailing requirements.

It is possible to use the pressure which exists in the supply line between the main control valve and the motor to operate an automatic device to bring in more cylinders when the load increases and the pressure in the supply line is built up accordingly. However as soon as more cylinders are brought into action the pressure in the supply line will drop in the ratio of the sum of the areas of the pistons that were originally working and the sum of the areas of the pistons which are now operative. This drop in pressure tends to cause the automatic device to go back to its original setting and cut out the group of cylinders just brought in, and this in turn would cause the pressure in the supply line to return to its original value, after which the whole cycle would start again.

The present invention has for its object to eliminate the phenomenon described above and to ensure positive and steady action of the hydraulic motor.

According to the present invention an hydraulically operated power apparatus having a plurality of cylinders or motors is provided with a selector valve device by which is controlled the number of cylinders or motors in operation, said device being sensitive to the pressure in the supply line and functioning when a predetermined critical pressure is attained to bring in a further cylinder, cylinders or motor, and when the pressure drops to a lower critical pressure functioning to cut out such cylinder, cylinders or motor.

The invention also comprises a multi-cylinder hydraulic motor with selector valve device as set

forth in the preceding paragraph wherein the higher critical pressure acting on the device and which determines the bringing into operation of a further group of cylinders is balanced by a lower hydraulic pressure plus the action of a compression spring, and the lower critical pressure, which determines the cutting out of the group of cylinders, is balanced by the action of said spring only, the hydraulic pressure which acted in cooperation with the spring being released when the said group of cylinders is brought into operation.

The said selector valve device may be amplified to operate in like manner to bring into operation a further group of cylinders when a critical pressure is again attained and to cut out both groups of cylinders when the lower critical pressure is attained.

The invention also consists in a multi-cylinder hydraulic motor having the cylinders operating in groups and provided with a selector valve embodying a piston valve sensitive to the pressure in the supply line and loaded by means of a spring in combination with hydraulic pressure, said piston valve operating when a predetermined critical pressure is attained in the supply line to bring in a further group of cylinders, the hydraulic pressure operating in combination with the spring being then released, and when a lower critical pressure is attained operating to cut out said group of cylinders under the action of its spring only, the hydraulic pressure being then readmitted to act in combination with the spring.

Such selector valve device may be provided with a plurality of such piston valves operating in sequence when a predetermined critical pressure or pressures is, or are attained in the supply line to bring in a corresponding number of groups of cylinders in the same sequence.

The invention will now be described by way of example with reference to the annexed drawing wherein:

Figure 1 shows diagrammatically a multi-cylinder hydraulic motor with a distributing valve for each cylinder, a main control valve and a selector valve device in accordance with the present invention, and

Figure 2 illustrates in section one form of distributing valve controlled by the selector valve device.

The motor is shown as comprising three groups, namely a group of three cylinders *a*, a second group of cylinders *b* and a third group of cylinders *c*, there being five cylinders in both the second and third groups. It will be understood that the number of groups and the number of cylinders

in the groups can be varied as may be found desirable. Each cylinder is provided with a distributing valve d by which pressure fluid is supplied to and exhausted from the cylinders. The distributing valves of the first group are always in operation when the motor is running but the distributing valves of the cylinders of the second and third group operate to supply and exhaust fluid to and from their cylinders only when they are brought into operation by the automatically operated selector valve device to be hereafter described.

Pressure fluid is supplied from an accumulator through a pipe line e to the inlet port e^1 of the valve body e^2 of the main control valve, in which is located a sliding piston valve e^3 having an annular recess e^4 , an axial bore e^5 and an operating arm e^6 . This valve body is provided with annular recesses e^7 and e^8 connected respectively by pipe lines f and f^1 to the distributing valve of the first group and a further recess e^9 with which communicates the port e^1 . To a port f^2 in the foot of said valve body is connected a pipe line f^3 connected through a back pressure valve f^4 to exhaust pipe line f^5 . The distributing valves of the second and third groups are connected through branch connections f^6 to the pipe line f^3 and also through branch pipe connections f^7 to a pipe line f^8 connected to pipe line f^1 .

The automatic selector valve device embodies a valve body g having three parallel bores h , i and j . Within the first bore are two pistons h^1 and h^2 , piston h^2 being of smaller diameter than piston h^1 . Piston h^1 is provided with a small annular groove h^3 which communicates through an axial passage h^4 in the piston with a chamber h^5 at the upper end of the first bore. At the foot of the piston h^2 is a chamber h^6 which communicates by way of a passage h^7 with a port h^8 which latter is connected to pipe line e through which fluid under pressure is supplied from the accumulator. Said port also communicates with an annular recess h^9 encircling piston h^1 . The said bore is further provided with a longer annular recess h^{10} surrounding the co-operating ends of the two pistons.

The second bore i accommodates a sliding piston valve i^1 provided with a broad annular recess i^2 and two smaller annular recesses i^3 and i^4 . At the upper end of said bore is a chamber i^5 in which is housed a helical compression spring i^6 which bears on a spring carrier i^7 and by which the said piston is resiliently loaded. Said bore is provided with an annular recess i^8 which communicates by a passage i^9 with the aforesaid chamber h^5 . Below annular recess i^8 is an annular recess i^{10} which communicates by means of a passage i^{11} and a pipe line i^{12} with the distributing valves of the second group of cylinders. A further annular recess i^{13} communicates by way of a passage i^{14} with the aforesaid annular recess h^{10} . Towards the foot of the second bore is a still further annular recess i^{15} while at the foot thereof is a chamber i^{16} which communicates with a port i^{17} . This port is connected by means of a pipe line i^{18} with pipe line f^1 .

Piston i^1 is provided with an axial passage i^{19} which places the recesses i^2 and i^4 in communication with each other and further passages i^{20} which place the recess i^3 in communication with the chamber i^5 .

The third bore j accommodates a sliding piston valve j^1 with broad annular recess j^2 and narrow recess j^3 . At the upper end of said bore is a chamber j^4 in which is housed a helical com-

pression spring j^5 . The latter bears on a spring carrier j^6 by which said piston valve j^1 is resiliently loaded. Said bore is provided with an annular recess j^7 which communicates by means of a passage j^8 with the annular recess i^8 .

Said bore is also provided with an annular recess j^{10} which is in communication with a port j^{11} , connected by means of pipe line j^{12} with the distributing valves of the third group of cylinders.

Below the annular recess j^{10} is a further annular recess j^{13} which communicates by way of a passage j^{14} with the aforesaid annular recess i^{13} and also with a port j^{15} which latter is connected by means of a pipe line j^{16} with the exhaust pipe line f^5 . At the foot of the third bore is a chamber j^{17} which communicates by passage j^{18} with the annular recess i^{15} .

The piston j^1 is provided with passages j^{19} which place the annular recess j^3 in communication with the chamber j^7 .

Each distributing valve d comprises a valve body k and a piston l working therein. Said valve body is provided with an inlet port k^1 connected to the pipe line f^1 , an exhaust port k^2 connected to the pipe line f^5 and a port k^3 connected to the corresponding cylinder of the motor.

The piston l is provided with an annular recess l^1 and a central bore l^2 which at its upper end is enlarged as at l^3 to receive the small piston l^4 .

The foot of the bore l^2 communicates with a transverse passage l^5 which in turn communicates with an annular recess l^6 in the valve body which recess communicates with a port l^7 to which is connected either a pipe line i^{12} or j^{12} .

The lower end of the piston l is provided with a recess l^8 in which is accommodated a helical compression spring l^9 . This spring bears on a crosshead m which carries a roller m^1 which bears on a cam track m^2 .

Normally the pistons l of the valves d for the second and third cylinder groups of the motor are maintained in their outer positions by the action of the springs l^9 , the cylinders being then open to exhaust through the ports k^2 . The cam track m^2 of the motor then merely raises and lowers the cross heads without imparting any movement to the pistons l . Should, however, pressure fluid be supplied to a port l^7 the pressure is transmitted to the underside of the small piston l^4 and as the upward movement of this small piston is restricted by the upper end of the valve body the piston l is forced downwards until the foot thereof co-operates with the cross-head. The piston l and crosshead m are moved in one direction by the operation of the cam track and moved in the other direction by the pressure in the enlarged bore l^3 , the reciprocating movement imparted to the piston opening the corresponding cylinder to pressure and exhaust alternately.

It will be assumed that the motor is used to drive a winch and that it is desired to raise a load thereby. The arm e^6 is therefore operated so that the piston valve e^3 is lowered to permit pressure fluid from the accumulator to pass through pipe line e , port e^1 , valve body, pipe line f^1 and the distributing valves of the first group d , thus supplying pressure fluid to the ports l^7 and k^1 thereof and lowering the pistons l , whereby pressure fluid is admitted through the ports k^3 to the cylinders of said group, the fluid being exhausted upon lifting of the piston l .

by the cam rollers m^1 (as heretofore described) through the ports h^2 , pipe line f , annular recess i^7 , axial bore e^5 and pipe line f^3 to the exhaust pipe line f^5 . The motor is then driven by the three cylinders of the first group.

Pressure fluid from the accumulator passes through port h^8 and passage h^7 to act on the underside of piston h^2 so that piston h^1 places the fluid in chambers h^5 , i^5 and j^4 and interconnecting passages under a pressure somewhat less than that of the pressure fluid supplied by the accumulators.

The pressure of the fluid in the supply line is transmitted by pipe line j^8 and port i^7 to the chamber i^6 . When, due to increase of the load on the motor, such pressure becomes sufficiently great to overcome the pressure of the fluid acting on the upper end of piston valve i^1 and also the spring i^6 said valve moves upwards. The upper lap of said valve then seals the end of passage i^9 , thus cutting off the supply of fluid under pressure to chamber i^6 , and the annular recess i^3 , in which terminate the passages i^{20} , registers with the annular recess i^3 . As the latter communicates through passage j^{14} , annular recess j^{13} , port j^{15} and pipe line j^{16} with the exhaust pipe line f^5 the chamber i^5 is thereby placed in communication with the exhaust pipe line. As the piston valve i^1 is then loaded only by its spring it then shoots upwards to the limit of its travel and the pressure of the fluid in chamber h^5 is then transmitted through passage i^9 , annular recess i^2 , passage i^{11} and pipe lines i^{12} to the distributing valves of the second group of cylinders, said valves being then caused to function so that the second group of cylinders in addition to the first group is brought into operation.

When the second group of cylinders has been brought into action the pressure in the operating cylinders falls to the value required to deal with the load under the new grouping. It should be noted that piston i^1 does not drop back to the cut out position, the position shown, as it is now loaded solely by its spring.

When piston valve i^1 is raised as aforesaid it places chamber j^{17} in communication with chamber i^{16} through passage j^{18} so that should the pressure in the supply line increase to the same or another critical value piston valve j^1 will likewise be raised.

Its first movement seals the end of passage j^8 and through the passages j^{19} places chamber j^4 in communication with annular recess j^{13} and therefore, through port j^{15} and pipe line j^{16} with the exhaust pipe line f^5 . As there is now only the pressure of the spring j^5 acting on the piston valve j^1 the latter shoots upwards to the limit of its travel whereon the pressure in chamber h^5 is transmitted through passages i^9 and j^8 , annular recess j^2 , ports j^{11} and pipe lines j^{12} to the distributing valves of the third group of cylinders so that the motor is now driven by all its cylinders.

When the load on the motor is reduced there is a corresponding decrease in pressure in the supply line and therefore in the chambers i^{16} and j^{17} and when such pressure is reduced to such a critical pressure that the springs i^6 and j^5 overcome the pressure acting on the underside of the piston valves i^1 and j^1 the latter are moved back towards their initial or cut out position shown in the drawing.

When the top laps of said piston valves uncover the annular recesses i^3 and j^7 the chambers

i^5 and j^4 are opened to the pressure of the fluid in chamber h^5 so that the said valves under the combined action of the fluid acting on the top thereof and their springs shoot back to the cut out position illustrated in Figure 1 so that passage i^{11} and port j^{11} are both opened to exhaust. The distributing valves of the second and third groups are thereby rendered inoperative so that the motor is again driven by only the first group of three cylinders.

In the event of piston valve i^1 returning to its initial position before piston valve j^1 the fluid in chamber j^{17} is exhausted through passage j^{18} , annular recess i^4 , passage i^{19} , passage j^{14} , port j^{15} and pipe line j^{16} , valve j^1 being then free to return to its cut out position.

Should there be a deficiency of pressure fluid in chamber h^5 and connecting passages, pistons h^1 and h^2 move up thereby bringing annular recess h^3 in piston h^1 into communication with the annular recess h^9 in its bore so that accumulator fluid is supplied to said chamber through said recesses and axial passage h^4 . Should there be an excess of fluid in said chamber and communicating passages said pistons are moved down so that annular recess h^3 then communicates with the annular recess h^{10} . The excess fluid then passes through said axial passage to be exhausted through passages i^{14} , j^{14} , port j^{15} and pipe line j^{16} , whereon said pistons assume their normal intermediate position as shown, being maintained in a balanced condition by the difference in the total pressure acting against the top of the larger piston h^1 and the bottom of the smaller piston h^2 which supports their weight. These two pistons together constitute a pressure reducing valve for limiting the pressure fluid normally admitted to the chamber h^5 and controlling the pressure therein to suit the conditions for proper functioning of the valves i^1 and j^1 .

Pressure fluid at a continuous pre-determined pressure somewhat less than accumulator pressure is thereby maintained in said chambers h^5 , i^5 and j^4 .

If desired where a plurality of such motors are combined to effect different movements in the same machine the selector valve device may operate to control both or all motors.

For example a crane may be provided with three such motors, namely a lifting and lowering motor, a luffing motor and a slewing motor. Where such combination is provided the distributing valves of the second and third groups of all motors are connected by means of pipe lines to the passage i^{11} and port j^{11} respectively. Consequently, according to the load on the crane hook, one or more groups of all three motors will be made operative by the same selector valve device but when the load is landed and the empty hook only has to be maneuvered all motors will operate on the first group only, i. e. the group which operates on light load conditions. Thus one selector valve device adjusts all three motors to the load being handled and ensures that the minimum amount of liquid from the accumulator is used when operating under light load conditions.

What we claim as our invention and desire to secure by Letters Patent is:

1. Hydraulic power transmission apparatus including in combination a plurality of hydraulically operated units arranged to divide the load between those which are operative at any time, and selector valve apparatus controlling the number of units in operation and including a

selector member acted upon in one direction by an operating force dependent upon the hydraulic pressure in the supply line to the units, means for applying a counterbalancing force to the selector member in the opposite direction and pressure responsive means which, when the selector member moves to a predetermined extent under the action of a critical operating force, bring into operation at least one additional unit and automatically reduce the counterbalancing force exerted on the selector member by an amount greater than the reduction in the operating force resulting from the increase in the number of operative units thus brought into operation.

2. Hydraulic power transmission apparatus as claimed in claim 1 in which the selector member when moved by the critical operating force permits hydraulic pressure from the supply line to act in one direction upon a second selector member, having means for applying a counterbalancing force thereto and means for reducing that counterbalancing force when it is moved under the action of critical pressure in the supply line to bring at least one further unit into operation.

3. Hydraulic power transmission apparatus including in combination a plurality of hydraulically operated units arranged to divide the load between those of them which are operative at any time and selector valve apparatus controlling the number of units in operation and including a selector valve device acted upon in one direction by the hydraulic pressure in the supply line to the units and in the other direction by a counterpressure of smaller value and by a spring, and serving when moved by a critical hydraulic pressure to bring in at least one additional unit and to cut off the counterpressure, leaving the device subject to the opposed pressures of the hydraulic pressure in the supply line and the force of the spring only.

4. Hydraulic power transmission apparatus as claimed in claim 3 in which the selector valve device includes a piston valve acted upon at one end by hydraulic pressure from the supply line and at its other end by a hydraulic counterpressure of smaller force and by a spring and means whereby when the valve moves due to the

occurrence of a critical pressure in the supply line, it brings into operation at least one additional unit and releases the hydraulic counterpressure.

5. Hydraulic power transmission apparatus as claimed in claim 4 in which the piston valve when it moves under the action of the critical pressure admits hydraulic pressure from the supply line to a pressure chamber at one end of a second piston valve the other end of which is subject to a small hydraulic counterpressure and the force of a spring and, when it is moved due to the occurrence of a critical pressure in the supply line also brings into operation at least one additional unit and relieves the hydraulic counterpressure acting on it.

6. A hydraulic power transmission including a plurality of hydraulic motors arranged to divide the load between those which are operative at any time and fluid supply means therefore, said motors being grouped in units, in combination with a selector valve for controlling the operation of said units individually, said selector valve having means responsive to an increase in pressure in said fluid supply to an operating unit for putting an additional unit into operation and means for maintaining said additional unit in operation for an indefinite time upon a reduction in the fluid pressure resulting from the coming into operation of an additional unit, said selector valve having means responsive to a pre-determined larger reduction in pressure to withdraw said additional unit from operation.
